UNITED STATES PATENT OFFICE.

GEORGE C. AMEND, OF DES MOINES, IOWA.

COMBINED COOLER DISPLAY CASE AND REFRIGERATOR.

Application filed May 28, 1923. Serial No. 641,897.

To all whom it may concern:

Be it known that I, GEORGE C. AMEND, a citizen of the United States, and a resident of Des Moines, in the county of Polk and State of Iowa, have invented a certain new and useful Combined Cooler Display Case and Refrigerator, of which the following is a specification.

The object of my invention is to provide 10 a combined cooler display case and refrigerator, especially adapted for use in meat markets, which may be easily manufactured and marketed at a comparatively low cost.

Still another object is to provide a case 15 especially adapted for containing meats in which there are provided a number of compartments so that the device may be utilized both as a display case as well as a refrigerator.

Still another object is to provide a 20 refrigerating system in the case, which is so positioned that the cold air therefrom will pass downwardly over the stock arranged in one of the compartments of the device, 25 and the cold air will then be forced through a passageway into the display portion of the case.

In this connection, it may be mentioned 30 that the cold air from the refrigerating apparatus will travel downward and will refrigerate any meats or other products which may be positioned below, and at the same time if it is desired, the cold air may be forced into the display portion of the case, 35 or the passageway leading into the display portion of the case may be closed and the fan stopped so that the entire structure will then serve as a refrigerator only.

My present invention is an improvement 40 over my patent issued to me November 15, 1921, No. 1,397,392.

With these and other objects in view, my invention consists in the construction, arrangement and combination of the various 45 parts of my device, whereby the objects contemplated are attained, as hereinafter more fully set forth, pointed out in my claims, and illustrated in the accompanying drawings, in which:

Figure 1 is a perspective view of my improved cooler display case and refrigerator, the door wherein access may be had to the motor and fan being shown open.

Figure 2 is a sectional view taken on line 50 2-2 of Figure 1; and

Figure 3 is a sectional view taken on line 3-3 of Figure 1.

In the accompanying drawings, I have used the reference character A to indicate generally my improved cooler display case 60 and refrigerator, which is provided with a pair of end walls 10, a bottom 11 and a top 12. The case A is also formed with a front wall 13 and a back 14.

The top 12 is preferably made of glass so 65 that articles within the case may be properly displayed therethrough.

The front 13 of the case A is formed with plates of glass 15 and 16. The plates of glass 15 and 16 are arranged in pairs spaced 70 slightly apart as in the ordinary refrigerating construction.

The end walls 10 are also formed with glass plates 17 and 18. The glass plates 17 and 18 are also of double construction 75 similar to the glass plates 15 and 16.

The case A is divided into four compartments B, C, D and E.

The compartment B, which is the upper one, is preferably for the display of meats 80 or the like and may be properly called the display compartment.

A partition member 19 separates the compartment B from the compartment C and serves as a supporting means for the goods 85 placed within the display compartment. The partition 19 sets snugly against the front wall 13 and may be slightly spaced from the rear wall or back 14.

The partition member 19 has its ends 90 spaced from the end walls 10 so as to provide the passages 20 and 21, the purpose of which will be hereinafter more fully set forth.

Below the partition member 19 is mounted a refrigerating apparatus 22. The refrigerating apparatus 22 is mounted upon a number of slats 23, which are spaced apart 95 so as to provide passageways 24.

The slats 23 extend from the front to the back of the case and are supported upon the 100 cleats 25.

Below the compartment C or refrigerating apparatus compartment, as it may properly be called, is the compartment D which serves as a refrigerating compartment and 105 is used for storing meats.

Sliding door members 26 are arranged in the back wall 14 and permit access into the compartment B.

The doors 26 have grooves formed in their 110

frames which receive the tongues 27 formed in the back wall 14 for permitting the sliding of the doors 26. The doors 26 are formed with glass plates 28.

5 The back wall 14 is also formed with a pair of doors 29 mounted on the hinges 30. The doors 29 permit access into the refrigerating apparatus compartment C.

10 In order to gain access into the compartment D, I provide the doors 31, which are mounted on hinges 32 and have locking members 33.

15 A partition member 34 separates the compartment D from the compartment E and serves to support the meats or the like, which are placed within the refrigerating compartment D.

20 The partition member 34 is mounted on a pair of cleats 35 which are fixed to the front and back walls 13 and 14 of the case A. The partition member 34 terminates short of the ends of the case A and forms the passageways 36 and 37.

25 One end of the partition member 34 and one end of the partition member 19 are connected together by a partition 38. The partition 38 extends from the front to the back wall of the case A and is spaced from one of end walls 10.

30 The passageways 21 and 37 connect together and form the passageway F. One end of the compartment E, which is below the partition member 34 opens into the passageway F.

35 Near the end of the case, opposite the passageway F is mounted a motor 38^a having the fan element 39 thereon. The partition member above the motor 38^a is slightly raised, as at 40, so as to accommodate the motor 38^a.

40 A short wall 41 connects one end of the member 40 to the partition 34, as clearly shown in Figure 3 of the drawings. The wall 41 is provided with an opening 42, which is in communication with the compartment E.

45 One side of the member 40 is supported upon a vertical member 43, as clearly shown in Figure 1 of the drawings.

50 A hinge door 44 having the locking element 45 thereon is so arranged that access may be had to the motor 38^a through the door opening of the door 44.

55 In this connection, it may be mentioned that the cold air from the refrigerating apparatus 22 will pass downwardly through the passageways 24 and into the compartment D. The cold air from the compartment D will then have to pass through the passageway 36 where the air will then be forced by the fan element 39 in the direction indicated by the arrows 46 through the compartment E, and through the passageway F.

60 A pair of closure members 47 and 48 are mounted in the passageways 21 and 20 re-

spectively. When the closure member 47 is in position shown in dotted lines in Figure 3, then the cold air will be forced upwardly through the passageway F into the display compartment B. The air will then pass 70 from one end of the case to the opposite end of the case and downwardly through the passageway 20 providing the closure member 48 is in the position shown in dotted lines in Figure 3 of the drawings. 75

The closure members 47 and 48 are controlled from the back of the case A, from the handles 49 and 50.

From the construction of the parts just described, it will be seen that the cold air from 80 the refrigerating apparatus will pass downwardly and then circulate through the compartment E, passageway F and compartment B.

When it is desired to use the structure 85 only as a refrigerating case, then the closure members 47 and 48 are moved to the position in solid lines in Figure 3 of the drawings and the fan element 39 is rendered inoperative.

90 The refrigerating apparatus will produce cold air which will pass downwardly through the passageway 24 and upon the goods placed on the partition member 34 and within the compartment D. 95

It will be understood that the display compartment B is used only when the meat market is open for business and that the circulation of cold air caused by the fan 39 is desirable. However, the refrigeration of 100 the meats within the rest of the case is desirable at all times.

It will be seen that I have provided a display case which also serves as a refrigerator so that I practically get a double use out of 105 a single refrigerating apparatus and case.

Some changes may be made in the construction and arrangement of the various parts of my invention, without departing from the real spirit and purpose of my invention and it is my intention to cover by my claims, any modified forms of structure or use of mechanical equivalents which may be reasonably included within their scope.

110 I claim as my invention:

1. A refrigerator show case having a display compartment, an apparatus compartment and a refrigerating compartment, said apparatus compartment being arranged between the display and refrigerating compartments, said case being provided with a passageway extending around the apparatus and refrigerating compartments, a refrigerating apparatus mounted in said apparatus compartment and a fan element positioned 120 below the refrigerating compartment adjacent one end thereof and arranged to draw the cold air from the refrigerating apparatus through the refrigerating compartment and force it through said passageway 125 130

into the display compartment, as and for the purpose stated.

2. A refrigerator show case having a display compartment, an apparatus compartment and a refrigerating compartment, said apparatus compartment being arranged between the display and refrigerating compartments, said case being provided with a passageway extending around the apparatus and refrigerating compartments, a refrigerating apparatus mounted in said apparatus compartment and a fan element positioned below the refrigerating compartment adjacent one end thereof and arranged to draw the cold air from the refrigerating apparatus through the refrigerating compartment and force it through said passageway into the display compartment, a closure member arranged in the passageway for preventing the cold air from passing into the display compartment when the fan element is rendered inoperative as and for the purposes stated.

3. A refrigerator show case having four compartments therein arranged one above another, the two intermediate compartments terminating short of the ends of the show case so as to form a pair of passageways, said passageways connecting the upper and lower compartments together, a refrigerating apparatus in one of said compartments, a fan element in the lower compartment for drawing cold air from the refrigerating apparatus through the intermediate compartments, and forcing it through the lower compartment, thence upwardly through one of the passageways and into the upper compartment and thence through the other of the pair of passageways whereby the cold air will travel in a complete circuit.

4. A refrigerator show case having four compartments therein arranged one above another, the two intermediate compartments terminating short of the ends of the show case so as to form a pair of vertical passageways, said passageways connecting the upper and lower compartments together, a refrigerating apparatus in one of said compartments, a fan element in the lower compartment,

ment for drawing cold air from the refrigerating apparatus through the intermediate compartments and forcing it through the lower compartment, thence upwardly through one of the passageways and into the upper compartment and thence through the other of the pair of passageways whereby the cold air will travel in a complete circuit.

5. A refrigerator show casing having four compartments therein arranged one above another, the two intermediate compartments terminating short of the ends of the show case so as to form a pair of vertical passageways, doors in said case for gaining access into said compartments, said passage ways connecting the upper and lower compartments together, a refrigerating apparatus in one of said compartments, a fan element in the lower compartment for drawing cold air from the refrigerating apparatus through the intermediate compartments and forcing it through the lower compartment, thence upwardly through one of the passageways and into the upper compartment and thence through the other of the pair of passageways whereby the cold air will travel in a complete circuit.

6. A refrigerator show case having a display compartment, an apparatus compartment and a refrigerating compartment, doors in the back wall of said case for gaining access into said compartments, said apparatus compartment being arranged between the display and refrigerating compartments, said case being provided with a passageway extending around the apparatus and refrigerating compartments, a refrigerating apparatus mounted in said apparatus compartment and a fan element positioned below the refrigerating compartment adjacent one end thereof and arranged to draw the cold air from the refrigerating apparatus through the refrigerating compartment and force it through said passageway into the display compartment, as and for the purposes stated.

May 21, 1923, Des Moines, Iowa.

GEORGE C. AMEND.
